UNITED STATES PATENT OFFICE.

HOWARD C. NOBLE, OF NEW BRITAIN, CONNECTICUT.

DESIGN FOR A CLASP-BUCKLE.

SPECIFICATION forming part of Design No. 19,447, dated November 26, 1889.

Application filed July 31, 1889. Serial No. 319,342. Term of patent 7 years.

To all whom it may concern:

Be it known that I, HOWARD C. NOBLE, of New Britain, in the county of Hartford and State of Connecticut, have produced a new and original Design for a Clasp-Buckle; and the following is declared to be a full and concise description thereof, reference being had to the annexed drawing.

The design consists in the shape of the clasp-buckle, as shown in the accompanying drawing, and as hereinafter described.

The design embraces elongated loops *a a*, and between the loops, attached to the side thereof at about the middle, is a circular

frame *b*, within which frame is the figure of an anchor, the same being attached to the circular frame at two or three points, so as to produce an open-work effect. The said frame *b* and loops *a* are shaped and their surface ornamented to indicate spiral strands, so as to represent a rope or cable.

I claim as my invention—

The design for a clasp-buckle, as shown and described.

HOWARD C. NOBLE.
